UNITED STATES PATENT OFFICE.

ALBERT L. SWETT AND WILLIAM H. SAMSON, OF MEDINA, NEW YORK.

DOOR-HANGER.

SPECIFICATION forming part of Letters Patent No. 254,245, dated February 28, 1882.

Application filed July 11, 1881. (No model.)

To all whom it may concern:

Be it known that we, ALBERT L. SWETT and WILLIAM H. SAMSON, of Medina, in the County of Orleans, in the State of New York, have invented new and useful Improvements in Door-Hangers, of which the following, taken in connection with the accompanying drawings, is a full, clear, and exact description.

This invention relates to improved means for carrying and guiding a suspended sliding door; and it consists, first, in a peculiar construction of the carrying-roller of the door-hanger, whereby the tread of said roller is enlarged in breadth to better sustain the door laterally without materially increasing the weight of the roller, and which also prevents, to a great extent, the clogging of the roller by snow and ice on the track-rail from which the door is suspended.

The invention also consists in a novel manner and means of securing to the door the roller which usually bears on the rear face of a guide-rail and guides the door in its movement, all as hereinafter fully described.

In the annexed drawings, Figure 1 is a front view of our invention; Fig. 2, a rear view of the same; Fig. 3, a section on line *x x*; Fig. 4, a plan view; and Fig. 5 illustrates modifications in the details of the attachment of the guide-roller.

Similar letters of reference indicate corresponding parts in all the figures.

A denotes the hanger or door-suspending arm secured to the upper part of the door, and *R* is the carrying roller or wheel pivoted to the arm *A*, and traveling on a plain track-rail, *C*, secured stationary above the door. The roller or wheel *R* we provide with two treads, *a a*, of equal diameter, and an intermediate circumferential recess, *r*, which latter separates the aforesaid treads, and is of a proper size to increase the breadth of the wheel, so as to effectually sustain the same laterally without materially increasing the weight of the wheel. The intervening recess, *r*, also allows any snow or ice which may be on the track to escape from under the two treads *a a* in the approach of the wheel, and thus serves to prevent the clogging of said wheel to a great extent.

c denotes the guide-roller, designed to guide and steady the door in its movement. Said

roller is usually made to travel in a longitudinal recess, *v*, in the under side of the track-rail, and has heretofore been pivoted either on an arm extended from the hanger-strap or on a separate strap secured to the rear face of the door. In either case the upper end of the spindle of the roller was unsupported laterally, and therefore liable to become bent or broken. Furthermore, the aforesaid connection of the roller with the hanger-strap rendered the latter difficult to mold and cast, and thus increased the cost of the manufacture of the same. The employment of the extra strap on the back of the door is also objectionable, in that its attachment defaces the rear or inner face of the door, and by its projection from said face frequently presents an obstruction which, in moving the door, comes in contact with the wall or side of the building, and either mars the same or completely stops the movement of the door.

To obviate the aforesaid defects, we pivot the roller *c* on top of the door by means of a pin, *e*, which passes vertically into the top of the door, and has its upper end sustained by a plate, *d*, which is applied across the top of the roller *c*, and secured to the door by bolts *b b*, passing vertically into the top of the door.

The plate *d* may be either straight, and supported over the roller by extensions *u* of the top of the door, at opposite sides of the roller, as shown in Fig. 2 of the drawings, or made with vertical offsets *o o*, and horizontal extensions *m* from said offsets, resting on the top of the door and secured by screws *b b*, as shown in Fig. 5 of the drawings. The pin *e* may be also sustained by a plate secured to the top of the door, and extended across the under side of the roller, as shown by dotted lines in Fig. 5 of the drawings.

Having described our invention, what we claim as new, and desire to secure by Letters Patent, is—

1. In a door, the combination of a plane-faced track and a carrying roller or wheel, *R*, mounted on said track, and having two treads, *a a*, of equal diameters, with an intervening circumferential recess, *r*, substantially as described and shown, for the purpose specified.

2. The combination, with a suspended sliding door, of the roller *c*, the plate *d*, extended over the roller and secured to the door by bolts
